ERIC W. BECKEMAN, OF PHILADELPHIA, PENNSYLVANIA, ASSIGNOR TO WESTINGHOUSE ELECTRIC & MANUFACTURING COMPANY, A CORPORATION OF PENNSYLVANIA

TURBINE NOZZLE BLOCK

Application filed March 21, 1930. Serial No. 437,766.

My invention relates to a nozzle block for a fluid pressure turbine, and it has for its object to provide an improved construction thereof.

A more particular object is to provide a construction whose efficiency is comparable to the efficiency obtainable by the most efficient known constructions but which is less expensive to make than such constructions.

Nozzle passages of circular cross-section and of rectangular or square cross-section have been used for directing motive fluid against a row of blades in a turbine. The round nozzles are inexpensive to manufacture and are individually efficient. However, a group of round nozzles in an arcuate row, as heretofore arranged with their discharge openings in juxtaposed relation, produces a form of jet which does not uniformly fill the passages between the blades, and which is unsuitable, therefore, for efficient action on turbine blading. The form of jet produced by said round nozzles consists of a number of individual round jets issuing from the individual nozzles. Consequently, as the blades pass the nozzle row, the flow of motive fluid from the jet through the blade passages, at least for the major portion of their height, is intermittent.

This produces eddying and a loss in efficiency. The height of the jet is less than the blade height for the major portion of the blade travel across the nozzle group, and the compression of the fluid caused by impact on the concave side of the blades results in expansion in a direction parallel to the height of the blade without doing useful work.

The square or rectangular nozzles may be disposed in juxtaposed relation in a group to provide a jet in the form of a continuous band of uniform width or height approximately equal to the blade height. Hence, the flow of fluid through the blade passages is uniform while passing along the nozzle row. The resulting efficiency is greater, but this form of nozzle is more expensive to make, requiring considerable skilled hand work.

In accordance with my invention, I form a row of nozzle passages of circular cross-section in a nozzle block, as by reaming or drill-

ing, adjacent nozzles being disposed to intersect and overlap the passage space of each other for a short distance from the discharge ends, and forming overlapping discharge openings in the exit face of the nozzle block. 55 Then, preferably, the ridges formed at the intersections are relieved to provide an elongated discharge opening of approximately uniform width for the group of nozzles.

The space provided by relieving the ridges permits the motive fluid to spread from the overlapping space, and a jet of approximately uniform width or height and of substantially uniform density is provided. Thus, I obtain the advantage of low cost of the round nozzle and the efficiency of the rectangular nozzle. 60 65

The above and other objects are effected by my invention, as will be apparent from the following description and claims taken in connection with the accompanying drawing, forming a part of this application, in which:

Fig. 1 is an elevational view of the discharge or exit side of the nozzle block;

Fig. 2 is a developed section along the line 70 II-II of Fig. 1 and also shows the row of blades against which the nozzles direct motive fluid;

Fig. 3 is a fragmentary perspective view looking into the nozzles from the discharge or exit ends; and

Fig. 4 is a sectional view, taken along the line IV-IV of Figs. 1 and 2.

Referring now to the drawing more in detail, I show in each of the figures, a nozzle block, indicated generally by the reference numeral 10, for expanding motive fluid in a turbine. The nozzle block is formed with a plurality of nozzles therein. For simplicity of illustration, only three nozzles, numbered 11, 12 and 13, are shown on the drawing, but it will be understood that any suitable number of nozzles may be employed. The nozzles terminate, at their discharge ends, in an exit face 14 (see Fig. 4), which may be slightly raised above the discharge side of the block. 85 90 95

The nozzles are circular in cross-section. Motive fluid enters the inlet end indicated at 15, and flows to the left through the nozzle. 100

It is discharged by the nozzles through the discharge openings 16, formed by the intersection of the nozzles with the exit or discharge face 14 of the nozzle block, and directed against the row of blades 17, disposed adjacent the exit face with a small clearance 18 therebetween.

The first step in the formation of these nozzles is a reaming or drilling operation.

10 In the present case, nozzles of expanding or increasing cross-section are shown; hence a reaming operation is employed. This leaves a septum wall 9 between adjacent nozzles as shown between the nozzles 11 and 12.

15 The nozzles are disposed in an arcuate row concentric with the axis of the turbine. Adjacent nozzles are disposed, by properly spacing their center lines, so that they intersect and overlap the passage space of each other 20 at the discharge ends. Inasmuch as the center lines of the nozzles diverge from the discharge ends toward the inlet ends, the amount of overlap decreases in the same direction, and hence the nozzles do not intersect 25 throughout their entire lengths but only for a distance from the discharge openings in the exit face. The overlapping of the nozzles at their discharge ends provides an overlapping of their discharge openings 16 in the exit 30 face, as shown at 19 in Fig. 1.

The extent of overlap, both transversely and longitudinally of the nozzles, may be reduced by increasing the angle between the center lines of adjacent nozzles. The center 35 lines of turbine nozzles are usually arranged to be tangential to the blade row at the points at which the center lines intersect the plane of the blade inlet edges. By disposing the center lines at a small angle above the tangents, the spacing and the amount of divergence between adjacent nozzle center lines is increased, and the amount of overlap is reduced. I have found that an angle of 5° above the tangent does not appreciably affect 45 the efficiency of the nozzles.

The center lines of the nozzles 11 and 12 are shown at 20 and 21, respectively. The center line 20 intersects the plane of the inlet edges of the blades 17 at 22, and as shown in Fig. 1, 50 is disposed at an angle of 5° above the line 23 which is the tangent at the point 22 to the circumference passing through the point 22. That is, the projection of the center line 20 in the plane of the blade inlet edges is disposed at an angle of 5° to the line 23, which is also in said plane.

The overlapping of the nozzles 11 and 12 begins, in the direction of flow, at the point 24 and increases toward the discharge ends. 60 The intersection of the nozzle surfaces, beginning at the point 24, extends along the lines 25 and 26 to the exit face 14, forming sharp-edged ridges 27 and 28.

The ridges between the nozzles 11 and 12 65 have been retained in the nozzle block, as

shown on the drawing, for the purpose of illustrating their formation after the drilling or reaming operation. The ridges between adjacent nozzles are preferably relieved, however, as is shown by the adjacent 70 portions of the block between the nozzles 12 and 13.

The relieving of the ridges begins near the point 24 and is first very slight, gradually increasing toward the discharge ends. The 75 amount of relieving at each part of the ridges is such as to compensate approximately for the amount of overlapping of the passage space, and the form of the relieving is such that the surface formed by the relieving is 80 at each part parallel to a transverse line connecting the center lines at said part.

This is illustrated in Fig. 4, in which the line 29 connects the center lines of the nozzles 12 and 13 in the plane of the section. The overlapping cross-sectional nozzle area is indicated at 31, and each ridge is relieved by an amount providing additional cross-sectional equal to one-half of said overlapping area. The surfaces 32 and 33 formed by relieving are, in each transverse plane, parallel 90 to the line 29.

The motive fluid from both of the adjacent nozzles, which is otherwise crowded by the overlapping of the nozzle passages, 95 spreads into the additional space provided by the relieving of the ridges along the intersection. A substantially uniform density of motive fluid discharging from the nozzles is thus provided. The discharge openings of 100 the nozzles in the row merge into an elongated common discharge opening.

The pitch of the nozzles, that is, the spacing between adjacent nozzles longitudinally of the row is so chosen that the amount of 105 relieving required to compensate for overlap provides an elongated common discharge opening of as nearly uniform width as possible. The jet of motive fluid discharging from the elongated opening is sufficiently 110 near uniform height to provide the desired efficiency.

While I have shown a detailed geometrical construction for obtaining the proper flow of motive fluid, it is not essential that the construction be exact in every detail in order to obtain good efficiency. For example, the inclination of the line 29 between the nozzle center lines changes at every point along the center lines. The surfaces 32 and 33 may, for practical purposes, be made parallel to the mean inclination of the line 29. I have also found that the overlapping arrangement alone of the adjacent nozzles, without removing the ridges 27 and 28, gives satisfactory 125 results. The clearance 18 provides some opportunity for the motive fluid from the overlapping passage space to spread, and apparently the height of the motive fluid jet entering the blade passages is quite uniform. 130

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

10. What I claim is:

1. A nozzle block having an elongated discharge opening of substantially uniform width in the exit face thereof and a plurality of nozzle passages of circular cross section terminating in said discharge opening, the curved surfaces of the nozzle passages extending to the exit face.

2. A turbine nozzle block having an exit face and having formed therein a plurality of round nozzles disposed in an arcuate row and having their curved surfaces terminating in the exit face, adjacent nozzles being disposed with their openings in the exit face overlapping in extent longitudinally of the row.

3. In an axial flow turbine, a rotating row of blades and a nozzle block therefor having an exit face and having formed therein a plurality of round nozzles disposed in an arcuate row and terminating in the exit face, the center line of each nozzle extending at a small angle to the tangent passing through the intersection of the center line with the plane of the blade inlet edges, and the openings in the exit face of adjacent nozzles overlapping each other in extent longitudinally of the row.

4. A turbine nozzle block having an exit face and having formed therein a plurality of round nozzles disposed in an arcuate row the curved surfaces of the nozzles terminating in said exit face, adjacent nozzles being disposed with their openings in the exit face intersecting each other and overlapping the area of each other.

5. A turbine nozzle block having formed therein a plurality of nozzles disposed in a row and ending in an exit face of the block, adjacent nozzles being disposed so that their openings in the exit face, defined by the intersection of the round surfaces and the exit face, intersect each other and overlap the area of each other, the block being relieved adjacent the points of intersection to provide an elongated discharge opening of approximately uniform width.

6. A nozzle block having an exit face and a plurality of expansion nozzles of circular cross section terminating at said exit face, the discharge openings in the exit face of adjacent nozzles intersecting each other and overlapping the area of each other, the block being relieved adjacent the points of intersection to provide a discharge area in the exit face approximately equal to the sum of

the areas of the exit face intersected by the nozzles individually.

7. A nozzle block having a plurality of nozzle passages of circular cross section formed therein, said nozzles being disposed in a row and so that the circular-cross-sectional spaces of adjacent nozzles intersect each other for a distance adjacent the discharge ends.

8. A nozzle block having a plurality of nozzle passages of circular cross section therein, said nozzles being disposed in a row and adjacent nozzles intersecting each other and overlapping the circular passage space of each other for a distance adjacent the discharge ends.

9. A nozzle block having a row of nozzles formed therein, said nozzles being circular in cross section, adjacent nozzles being disposed so that their curved surfaces intersect each other and to overlap the passage space of each other for a portion of their lengths at the discharge ends, said nozzle block being relieved along the intersection to provide additional passage space for fluid to compensate for the loss of passage space caused by the overlap.

10. A turbine nozzle block having a plurality of nozzles formed therein, said nozzles being disposed in an arcuate row and terminating in discharge openings in the exit face of the nozzle block, adjacent nozzles being disposed so that their curved surfaces intersect each other and overlap the passage space of each other for a short length adjacent the discharge ends, the ridges formed at the intersections of the nozzles being relieved to provide passage space to compensate for the loss of passage space due to overlap and to provide a discharge opening of approximately uniform width in the exit face.

11. A nozzle block for a fluid pressure turbine, said block having an exit face opposing a row of blades and a row of nozzles formed therein and terminating in said exit face, adjacent nozzles being disposed to intersect and overlap the passage space of each other for a distance at the discharge ends, the ridges formed at the intersections being relieved to provide additional passage space to compensate for the loss of passage space due to the overlap and to provide a discharge opening of approximately uniform width in the exit face for the row of nozzles, the area of overlap of adjacent nozzles in the exit face being substantially equal to the amount of relieving which is necessary to produce the discharge opening of approximately uniform width.

12. A nozzle block for an axial flow turbine and having a plurality of round nozzles therein disposed in an arcuate row, adjacent nozzles being disposed to intersect each other and to overlap the passage space of each other adjacent the discharge ends, the block

being relieved along the intersection to compensate for the loss of passage space caused by the overlap, the surface left by the relieving extending, transversely of the nozzles, approximately parallel to a transverse line 5 between the center lines of the adjacent nozzles.

13. A nozzle block having a plurality of nozzle passages of circular cross section formed therein, said nozzles being so disposed that the circular cross-sectional space along which the curved surface of one nozzle is formed occupies a portion of the circular-cross-sectional space along which the curved surface of the other nozzle is formed 10

15. In testimony whereof, I have hereunto subscribed my name this thirteenth day of March, 1930.
